UNITED STATES PATENT OFFICE.

EUGENE P. CAROLAN, OF SEGUIN, TEXAS.

DESIGN FOR A CABINET.

SPECIFICATION forming part of Design No. 24,079, dated March 5, 1895.

Application filed November 10, 1894. Serial No. 528,451. Term of patent 3½ years.

To all whom it may concern:

Be it known that I, EUGENE P. CAROLAN, of Seguin, in the county of Guadalupe and State of Texas, have invented and produced 5 a new and original Design for Document-Cabinets, of which the following is a specification, reference being had to the accompanying drawing.

In the drawing, is illustrated in perspective, 10 my cabinet shown with the door open, this view being deemed sufficient to fully illustrate the design.

The design comprises a rectangular body part or casing 1 having an open front closed 15 by a door 2 hinged at one side of the casing. Within the case is located a horizontal partition 7.

6 indicates a vertical partition defining the

compartment below the partition 7 into two compartments which are subdivided, respectively, by a plurality of horizontal partitions. Above the partitions 7 are two horizontal partitions extending entirely across the cabinet defining superimposed horizontal compartments 4 and 5 and a horizontal compartment 25 which is subdivided by a plurality of vertical partitions into pigeon holes 3.

What I claim is—

The design for a document cabinet, substantially as herein shown and described. 30

In testimony of all which I have hereunto subscribed my name.

EUGENE P. CAROLAN.
